CLAIM

The ornamental design for a clothes management apparatus, as shown and described.

DESCRIPTION

FIG. 1 is a top, front and left side perspective view of a clothes management apparatus showing my new design; FIG. 2 is a bottom, front and right side perspective view thereof;

FIG. 3 is a bottom, rear and right side perspective view thereof;

FIG. 4 is a top, rear and right side perspective view thereof;

FIG. 5 is a front elevational view thereof;

FIG. 6 is a rear elevational view thereof;

FIG. 7 is a left side view thereof;

FIG. 8 is a right side view thereof;

FIG. 9 is a top plan view thereof;

FIG. 10 is a bottom plan view thereof;

FIG. 11 is an enlarged view of portion 11 in FIG. 3; and, FIG. 12 is an enlarged view of portion 12 in FIG. 3.

The dashed broken lines in the drawings illustrate portions of the clothes management apparatus that form no part of the claimed design. The dot-dashed broken lines shown in FIGS. 3, 11 and 12 illustrate detail markers for the enlarged detail views and form no part of the claimed design.
